United States Patent Office.

JOHN H. PARRISH, OF GREENSBOROUGH, ALABAMA.

Design No. 4,557, dated January 3, 1871.

DESIGN FOR A LAND-MARK.

The Schedule referred to in these Letters Patent and making part of the same.

I, JOHN H. PARRISH, of Greeusborough, in the county of Hale and State of Alabama, have invented and produced a new and original Design for Cast-Iron Land-Mark or Monuments, of which the following is a specification.

The nature of my invention is represented in the accompanying drawing, to which reference is made.

The arrow cast upon the top is to show the direction of the meridian passing through the corner marked, and the star at its center shows the precise location of the corner in the ground.

The projection at the foot is to keep the monument in place when firmly placed in the ground.

The numbers of the township, sections, and lots are to be designated by letters and figures, cast or otherwise placed upon the respective sides, facing said townships, sections, or lots.

I claim as my invention—

The design for a cast-iron land-mark or monument, substantially as shown and described.

JOHN H. PARRISH.
